and method of forming such a lining and of producing the same. The invention is particularly adapted for use in containers having circular bottoms, such as barrels, kegs, drums, etc., and is particularly adapted for use in containers having bottoms which are not perfectly circular, such as kegs, barrels, drums, etc., which have bottoms which are slightly irregular, or which are slightly flattened or which have bottoms which are slightly rounded or which have bottoms which are slightly irregular.

UNITED STATES PATENT OFFICE

EDWIN D. GREENE, OF NEW YORK, N. Y., ASSIGNOR TO ARKELL SAFETY BAG COMPANY, OF NEW YORK, N. Y., A CORPORATION OF NEW YORK

BAG OR LINING AND METHOD OF PRODUCING THE SAME

Application filed January 29, 1931. Serial No. 511,942.

Crinkled paper linings for containers are usually made of a single piece of crinkled paper that is folded over on a line extending in the general direction of the crinkles in the paper with the margins of its longitudinal edges and the edges of one end folded over and sewed. In some cases, also the longitudinal edge portions of the bag blank either before or after closing the end of the bag tube are tucked in. In using such a bag blank as a lining for containers, it is opened up or ballooned, usually by swishing it through the air with its open end foremost, and while in open condition is inserted in the container. In the case of barrels, kegs and other containers having circular bottoms, it is difficult to properly lay the unformed bottom end of the lining on the circular bottom of the container, and even where care is exercised bulky folds are likely to occur at the bottom of the lining which, of course, is objectionable. It has been proposed to form a flat bottom in the bag blanks or linings before shipment to the user but such pre-forming of the bottoms adds materially to the expense of the linings.

One of the objects of the present invention is to provide a bag blank having an unformed bottom end which may be easily and quickly inserted in a barrel or other container having a circular bottom so as to closely fit the container.

With this object in view, one of the features of my invention consists in the provision of a scoring or crease in the bag blank which is so located that upon merely ballooning the bag in the usual manner, the closed end of the lining takes a substantially circular form which upon insertion of the lining in the container uniformly flattens out and closely fits the bottom of the container.

Another object of my invention is to provide a lining of the character indicated of novel and improved construction.

Another object of my invention is to provide a novel and improved method of forming a lining of the character indicated.

Referring to the drawings,

Figure 1 is a view in perspective of one

form of my improved bag blank previously to being inserted in a container;

Fig. 2 is a side view of the bag blank, while it is in inflated condition, and ready to be inserted in the container;

Fig. 3 is a bottom plan view of the blank as it appears when inserted in a container;

Fig. 4 is a view of the inner side of the bottom of the lining after insertion in the container;

Fig. 5 is a view corresponding substantially to Fig. 1 but showing a slightly modified construction;

Fig. 6 is a view in perspective showing the bag blank partially inflated preliminary to inserting in the container;

Fig. 7 is a view in perspective of the bottom of the lining as it appears after insertion in the container;

Fig. 8 is a plan view of the inner side of the bottom of the lining; and

Figs. 9 and 10 are detail sectional views respectively taken on the lines 9—9 and 10—10 of Fig. 5.

The lining illustrated in the drawings is particularly adapted for barrels, kegs and other containers having circular bottoms. The bag blank as illustrated in Fig. 1 may be formed in the usual manner by folding a sheet of crinkled paper upon itself and folding over and stitching the longitudinal edges as indicated at 2 and similarly forming a seam at one end of the folded sheet as indicated at 4. In the form shown in Fig. 1 the bag blank is provided with a scoring or crease on a line 6 parallel with the seam 4 and spaced a distance from the seam corresponding substantially to the radius of the bottom of the container. The bag blank is also provided with lines of stitches 8 extending diagonally across the corners of the closed end of the blank from the crease 6. The upper ends of these lines of stitching are spaced apart a distance corresponding substantially to the diameter of the bottom of the container. The scoring or crease 6 may be formed in any suitable manner either before or after the bag blank is made up.

Preparatory to inserting this lining in the container, it is opened up in the usual man-

ner by swishing it through the air with its open end foremost. Owing to the pliability of the crinkled paper, as the lining is thus opening up, the closed end thereof tends to flatten out from the crease 6, so that when the bag is ready to be inserted in the container its bottom takes a substantially flat and circular form, corresponding substantially to the diameter of the container. Al- 10 so, owing to the lines of stitches 8 the projecting corners tend to fold over as indicated in Figure 2 so that upon placing the bottom of the lining on the bottom of the container the corners readily lay down flat against the container, and thus a substantially uniform flat bottom is formed in the bottom of the lining which closely fits the bottom of the container.

While it is preferred to provide the 20 stitches 8 so as to cause the corners to be folded over easily as the lining is inserted in the container, in place of these stitchings the linings may be creased across the corners, or if desired the corners may be folded over before ballooning the bag. In fact it has been found that even without such provision for folding over of the corners, that the mere provision of the crease 6 assists materially in properly fitting the lining to the container.

30 In the form shown in Figs. 5 to 10, inclusive, the bag blank is initially formed in a well known manner by tucking in the longitudinal edges 10 thereof before forming the end seam in the bag blank, and the ends of 35 the tucked-in longitudinal portions are stitched in with the end of the bag tube.

In accordance with my invention, a scoring or crease 12, corresponding to the scoring or crease 6, is provided in the bag blank 40 parallel with the end seam of the bag blank and spaced a distance therefrom correspondingly substantially to the radius of the bottom of the container.

45 During the usual inflation of the bag, the end of the bag blank tends to flatten out from the crease 12 until it reaches a substantially flattened condition, and upon insertion in the container it naturally flattens throughout its area on the bottom of the 50 container as indicated in Figs. 7 and 8.

As will be evident to those skilled in the art, my invention permits various modifications without departing from the spirit thereof or the scope of the appended claims.

55 What I claim is:

1. In a lining for containers of the class described, comprising a flat bag blank of crinkled paper having one end and its longitudinal edges closed and having its crinkles 60 extending longitudinally of the blank, the improvement which consists in said blank, having a peripheral crease spaced a distance from the closed end thereof to assist in forming a substantially flat bottom in the lining 65 when the lining is opened, said crease de-

fining the outer edge of the bottom thus formed and said bottom being adapted to substantially fit the bottom of the container.

2. A structure according to claim 1 in which the longitudinal edges of the bag 70 blank are tucked in.

3. A structure according to claim 1 in which a line of stitching extends from said crease diametrically across each of the corners at the closed end of the bag blank.

4. In a lining for a container having a circular bottom of the class described comprising a flat bag blank of crinkled paper having one end and its longitudinal edges closed and having its crinkles extending longitudinally of the blank, the improvement which comprises said blank having a peripheral crease spaced a distance from the closed end thereof corresponding substantially to the radius of the bottom of the container to assist in forming a substantially flat bottom in the lining when the lining is opened, said crease defining the outer edge of the bottom thus formed and said bottom being adapted to substantially fit the bottom 90 of the container.

In testimony whereof, I have signed my name to this specification.

EDWIN D. GREENE.
